APPARATUS FOR PRODUCING CASTINGS

Joseph E. Johnson, Brooklyn, N. Y.

Application April 18, 1940, Serial No. 330,287

9 Claims. (Cl. 22—57)

This invention has for its principal object the production of a machine for producing in an expeditious, facile and novel manner an exact and faithful reproduction or facsimile of an object, such as an insignia, inscription, cameo, intaglio etc., which has been placed in a die or which forms a part thereof. The invention is peculiarly adapted in its application to metals having a high melting point.

Further and other objects of the invention will be apparent as the description thereof proceeds.

According to the preferred form of the invention, the metal as, for instance, steel or other material from which the casting is to be formed, is employed in the process in shaped or block form, as a rod or bar or a disc or roller and a portion thereof is fused or brought to molten or liquid state by the application of heat, such for instance, by means of the well known electric arc method in which the metal material itself forms one of the electrodes. The end of the rod or bar, or if a disc or roller is employed, its periphery is then fused and forced quickly in molten condition into the die and pressure is then applied to the molten metal within the die, the pressure-applying means preferably being the unmolten or relatively cool portion of the metal work or material itself.

In the several figures of the accompanying drawings showing a practical embodiment of the apparatus of the invention:

Fig. 1 is a top plan view of such apparatus.

Fig. 2 is a side elevation thereof.

Fig. 3 is a vertical cross-section on the line 3—3 of Fig. 2.

Fig. 4 is a horizontal cross-section on the line 4—4 of Fig. 3.

Fig. 5 is a sectional view of a modification taken on the line 5—5 of Fig. 6, and

Fig. 6 is a vertical cross-section of the modification taken on the line 6—6 of Fig. 5.

Referring in detail to the drawings and, for the present, more particularly to Figs. 1 to 4 inclusive:

A walled chamber within which the process of the invention is carried on is indicated at 10. Said chamber is provided with a base 11, a front wall 12 detachably secured to the chamber, as by screws 13, whereby access to the interior of the chamber may readily be had, and an inwardly extending annular flange as shown forming a bearing member for a work-holder as will be herein described. A rotatable work-holder is indicated at 15 and carries the work 16 from which the casting is to be formed. In the preferred form

of the invention the work comprises a rod of suitable fusible and preferably metallic material, such as steel. This steel rod extends downwardly through the work-holder and into the chamber, as shown, and it is slidably and adjustably held in said work-holder in any desirable manner, as by set-screw 17 passing through the work-holder into engagement with the rod 16.

The upper end of the work-holder 15 is reduced in character as at 18 and extends through and is journaled within a cross-bar 19. The ends of said cross-bar are provided with guiding pins 20 slidably received within slots 21 of angled vertical supporting arms 22, the angles of which are detachably secured to the upper portion or wall of the chamber by means of adjustable screws 23. Tension springs 24 are connected to said screws and to the cross-bar 19 and constantly urge movement of the cross-bar 19 downwardly and accordingly movement of the work-holder 15 in the same direction with the guiding pins 20 engaging with the slots 21. A ball-race 25 may be provided and is interposed between the cross-bar 19 and work-holder 15 to decrease the effect of friction between the cross-bar 19 and work-holder 15 when the latter element is rotated. To permit connection between the cross-bar 19 and work-holder 15 while permitting rotation of the latter, I have provided a strap 25' fastened to the cross-bar and slidably engaging beneath an annular flange 25'' with which the work-holder is provided.

A rotatable sleeve is indicated at 26. Said sleeve is rotatably journaled within an inwardly extending flange or wall 27 herein before referred to and preferably integral with the side walls of the chamber 10 and it is provided with an annular sleeve 28 acting as a stop to limit the upward vertical movement of said sleeve within said flange or wall 27. The sleeve 26 and work-holder 15 are splined together by means of a key 29 on the sleeve which enters a slot 30 in the work-holder. This connection permits vertical movement downwardly of the work-holder 15 within the sleeve but prevents relative rotation of one member with respect to the other.

The upper end of the sleeve 26 is provided with a toothed gear or pinion 31 detachably fastened thereto in any desirable manner whereby it is rotatable with said sleeve. The teeth of the pinion 31 mesh with the teeth of a slideable rack 32 guided in its movement by an angle-bar 33 fastened to a wall of the chamber. One end of the rack is adapted to enter a suitable slot 34 in a wall of the chamber and the other end has a shank 35

journalled in and extending through an opposite wall and terminating in an operating handle 36. Obviously, reciprocation of the rack 32 by the handle 36 will rotate the sleeve 26 and consequently the work-holder 15 which carries the rod 16 with it.

A slideable die-support, slideable on the base 11, is indicated at 37. Said support detachably carries a metallic die 38 thereon which contains the impression from which the casting is to be made. In its base the die is provided with suitable openings for frictionally receiving pins 39 whereby removal and substitutions of different dies may readily be made with facility after removal of the detachable front wall 12. The die-support is received in an opening in a wall of the chamber and the opposite wall is provided with a screw-threaded opening receiving an adjustable screw 40. Said screw acts as a stop to limit the movement to the left (Fig. 3) of the support 37 on the base 11 and by adjusting said screw, the die may be brought into exact vertical alignment with the rod 16.

An actuating rod or bar is indicated at 41 and terminates in a handle 42. Said rod is pivoted at 42', as shown, to a bracket 43 fastened to a wall of the chamber and it is also connected by a pin and slot connection 44 to the die-support 37. A horizontally slideable rod comprising an electrode is indicated at 45. Said rod is slidably received by an insulating bushing 46 mounted in a wall of the chamber and it is pivotally connected to the end of actuating rod 41 by a pin and slot connection 47. Insulating material surrounds this last-named connection, as illustrated, to prevent short circuiting.

A bracket 48 is mounted on a wall of the housing and has an arm 49 pivoted thereto as at 49'. The lower end of said arm 49 engages a lug or projection 50 made of an insulating material and carried by the rod 45. The upper end of said arm 49 is connected by a pin and slot connection 51 to a locking arm 52 journalled in a wall of the housing and terminating at its inner end in a locking member 53 having an opening 54 of a size permitting it to normally loosely receive the work-holding member 15. One side of the opening 54 is beveled as at 55 and is adapted to be received by an annular notch 56 in the member 15 to hold and detachably lock it in elevated position against the action of the springs 24. A compression spring 56' is interposed intermediate the arm 49 adjacent its upper end and a wall of the chamber and urges said arm to swing in a clockwise direction to retain the member 15 in raised and locked position.

A binding post is indicated at 57 and is provided with a shank entering a bore 58 extending through a wall of the chamber. A compression spring 59 is mounted in said bore intermediate the shank of the binding post and a terminal 60 also mounted in the bore and having wiping electrical contact with the sleeve 26. A conductor 61 is fastened to the binding post 57 and is connected to a source of current supply (not shown) while another conductor 62 is also connected to said source of current supply and to the electrode 45.

The apparatus is shown in inoperative position with the metal die 38 shielded by a baffle plate 63 to prevent the introduction of dirt or other foreign matter into the die and which may be formed as an integral part of a wall of the chamber. I have also provided means for visual inspection of the end of the rod 16 in order to inspect its physical condition while being subjected

to the fusing process. Said means comprises a tube 64 extending through the wall 12 and in horizontal alignment with the end of the rod 16. Mounted on the outer end of said tube exteriorly of the chamber is a head 65 carrying a transparent plate 66, preferably of glass. This arrangement prevents the entrance of air into the chamber which is desirable in some cases as I have often found it expedient to carry on operations within the chamber in a vacuum or partial vacuum to prevent scaling of the rod 16 or the casting to be formed therefrom and which also enhances the fusing operation by the electric arc method.

Assuming the parts are in the positions shown, the operation of the apparatus is as follows:

The rod 41 is thrown to the right on its pivot 42' (Fig. 3) in order to bring the inner end of the electrode 45 into contact with the lower end of the rod 16 to establish the completion of the electrical circuit through the end of the rod and the electrode. The rod 41 is then moved slightly to the left or in a clockwise direction to space the end of the rod 16 and the end of the electrode 45 whereby an electric heating arc between the members is established. Meanwhile fusing of the end of the rod 16 proceeds and while so proceeding the rack 33 is reciprocated backwardly and forwardly to thereby rotate the rod in an obvious manner and thereby secure a uniform fusion thereof at all places adjacent its lower end. When said end has reached the necessary degree of plasticity as determined by visual inspection thereof in the manner previously described, the rod or bar 41 is thrown completely to the left on its pivot in a clockwise direction and as indicated at the left in dotted lines in Fig. 3. This, obviously carries the die 38 on its support 37 into vertical alignment with the end of the rod 16, retracts the electrode 45 and releases the locking edge 55 from its engagement with the notch 56 whereby the work-holder 15 slides downwardly within the sleeve 26, assisted by the action of the springs 24, and the molten metal on the end of the rod 16 is brought within the die 38 and is compressed therein by the unfused or unmolten part of said rod 16 to form the casting which conforms in configuration to the inner configuration of the die 38. After the casting is so formed and sufficiently cooled, the work-holder 15 carrying the rod 16 with the formed casting on the end thereof is manually raised by means of the cross-bar 19 to its initial position and locked in that position by swinging the rod or bar to inoperative or vertical position shown in full lines in Fig. 3 to permit the action of the spring 56' to bring the holder 15 and locking member 53 into interlocked engagement. The formed casting may then be cut off from the end of rod 16 at desired length. As the operating length of the rod 16 becomes shortened because of successive operations and the fusing of its end and the formation of successive castings, it may be lengthened by loosening the set-screw 17 and forcing the rod downwardly within its holder. It will be found that castings produced by the process described herein do not require re-hardening as they are sufficiently hardened by the quick cooling effect of the metallic die 38. This sudden chilling of the softened metal on the end of the rod 16, furthermore, prevents it from sticking to the die as is obvious.

In the modification illustrated in Figs. 5 and 6, the metal or other material from which the casting is formed is preferably in the form of a disc

or roller indicated at 67 and is detachably mounted in any manner on a separable or two-part shaft 68 the ends of which are journalled in opposite walls of the chamber. The casting in this case becomes a part of the peripheral edge of said disc or roller. The shaft is prevented from horizontal movement in one direction by a washer and set-screw indicated generally at 69 and the other end of the shaft is provided with a crank 70 for the purpose of rotating it.

The die 71 is slideable and extends within suitable slots 72 formed in the body of the chamber and which guide the die in its movement. Said die is grooved as at 73 in its face or side adjacent the disc or roller 67, said groove containing the object or inscription etc. which it is desired to reproduce by a casting. A bracket 74 is fastened to a wall of the chamber and a bar or rod 75 is pivoted thereto, as by pivot 76. The upper end of said bar is connected by a pin and slot connection 77 to a detent slide or rod 78 extending through an opening in a wall of the housing which slidably supports it. The inner end of said detent slide normally engages beneath the end of the die 71 to hold it in inoperative or retracted position.

A rod 79 is secured to the upper end of the die 71 or it may be integral therewith. Secured to the said rod 79 is a cross-arm 80 and tension springs 81 are fastened to said cross-arm adjacent its ends and to an upper wall of the chamber. The action of said springs 81 tends to slide the die 71 downwardly within the slots 72 as is obvious.

The bar or rod 75 terminates at its lower end in a handle 82 and said bar or rod is connected by a pin and slot connection 83 to an angle bar, the horizontal leg of which is indicated at 84 while its vertical leg is indicated at 85. The vertical leg 85 may be supported by a pin or bolt 86 extending loosely therethrough and into the body of the housing and a compression spring 87 encircles said pin or bolt and bears against said leg and housing and tends by its action to retain said leg a spaced distance from said housing.

A pin and slot connection 88 connects the upper end of the leg 85 to an electrode 89 slidably mounted in an insulated bushing 90 in a wall of the chamber, said pin and slot connection being surrounded by insulating material as in the previous case. A conductor 91 is connected to a source of current supply and to the outer end of electrode 89 while conductor 92 is connected to the same source of current supply and to a wall of the chamber.

As in the previous case, the handle 82 is manipulated in the proper direction to bring the inner end of the electrode 89 into contact with the periphery of the disc or roller 67 to establish the electrical circuit. It is then again manipulated slightly to space the roller from the end of the electrode whereby a heating electric arc is made to fuse the peripheral edge of the disc or roller. When the proper degree of plasticity of such edge has been reached the handle is swung in such manner as to release the detent 78 from engagement with the die or mold 71 which travels downwardly under the influence of springs 81 and the fused metal on the peripheral edge of the disc or roller 67 enters the groove 73 in the die to form the desired casting on the edge of the disc, the unfused and comparatively cool portion of the disc providing sufficient pressure and resistance for the formation of the casting. Said disc, with the finished casting thereon, is then removed and a

new one substituted for repetition of the same operation. As in the previous case, the cool die prevents the heated metal on the edge of the disc from sticking thereto.

5 I have shown in this modification a device for feeding a powdered carbonized material to the fusing metal for hardening the metal and casting which obviously could be employed in the preferred form of apparatus, if so desired. A 10 hopper 93 for holding the powdered carbonized material 94 is fastened to a wall of the chamber by brackets 95. This hopper interconnects with a feed tube 96 directed toward the peripheral edge of the disc or roller 67. The passageway 15 between the hopper and tube may be open or closed by a handled spindle or plunger 97. When the edge of the disc or roller 67 has reached the desired degree of plasticity the carbonized material is permitted to fall thereon by opening the connection between the hopper and feed tube 96, the disc or roller 67 being continuously rotated by the crank 70, as is manifest.

The invention claimed is:

1. In an apparatus of the character described, a casing having a work chamber, means for supporting in said chamber a solid mass of material from which a casting is to be produced, a die in the chamber, said die and supported body of material being normally disposed in spaced relationship, a device movable into and out of working position in the chamber for fusing a portion of said material, and means for relatively moving the supporting means and die to bring the die and fused portion of the material into contact to form the casting.

2. In an apparatus of the character described, a casing having a work chamber, means for supporting in said chamber a solid mass of material from which a casting is to be produced, means carried by the casing for rotating said supporting means and material, a die in the casing, said die and supported body of material being normally disposed in spaced relationship, a heating device movable into and out of working position in the chamber, for fusing an edge of said material, and means for relatively moving the supporting means and die to bring the die and fused portion of the material into contact to form the casting.

3. In an apparatus of the character described, a normally closed chamber, a support in the chamber for the material from which a casting is to be produced, means for rotating said support, means for fusing an edge of said material, a die in said chamber for action on the fused material, and means for bringing the die and fused edge of the material into cooperative relation to form the casing, a sight device mounted in sealing engagement with a wall of the chamber for permitting visual inspection of the material during the fusing operation.

4. In an apparatus of the character described, a chamber, a support in the chamber for the material from which a casting is to be produced, means for rotating said support, a hopper containing a powdered carbonizing chemical mounted on said chamber and provided with an outlet adjacent the material, means for opening or closing the outlet, means for fusing a portion of the material and a die for receiving said fused portion to form a casting.

5. In an apparatus of the character described, a casing providing a work chamber, a holder for supporting a metallic rod forming a work piece from which a casting is to be produced, said holder supporting said metallic rod for longitudi-

nal feed movement in the chamber, means for rotating said holder, a detent for engagement with said holder for retaining it in one position against longitudinal feed movement, means mounted in the casing for fusing a portion of the rod disposed within the chamber, a die in the chamber, and means for releasing said holder for longitudinal feed movement toward the die to cause the fused metal to enter the die and to be compressed by said rod.

6. In an apparatus of the character described, a casing providing a chamber, a holder for supporting a metallic rod forming a work piece from which a casting is to be produced, said holder being mounted for downward travel in the casing to impart feed movement to said rod, a detent engaging said holder for retaining it in raised position in the chamber, a sleeve splined to said holder, a pinion carried by said sleeve, a reciprocatory rack mounted on the casing and engaging said pinion and adapted by movement thereof to rotate said sleeve and holder, means for fusing a portion of said rod, a die in the chamber, and means for releasing said detent to permit said holder to move to bring the fused portion of the rod into contact with said die.

7. In an apparatus of the character described, a casing providing a work chamber, a holder for supporting a metallic rod forming a work piece from which a casting is to be produced, said holder mounting said metallic rod for downward travel in the chamber, a detent engaging said holder for retaining it in raised position in the chamber, means urging movement of said holder downwardly in the chamber against the action of said detent, a sleeve connected to said holder while permitting longitudinal movement of said holder therein, means for rotating said sleeve and holder, means for fusing a portion of said metallic rod, a die in the chamber, and means

for releasing said detent to permit said holder to move downwardly to bring the fused portion of the metal rod in contact with the die to form the casting.

8. In an apparatus of the character described, a casing providing a work chamber, a holder for supporting a metallic rod forming a work piece from which a casting is to be produced, said holder mounting the rod for downward movement within the chamber, an electrode, a source of current supply connected to said rod and electrode for establishing an electric heating arc therebetween to fuse a portion of said rod, a die in the chamber, a detent for retaining said holder and rod normally elevated in the chamber and spaced from said die, and means for varying the distance of said electrode from said rod and for releasing said detent to allow said holder to move downwardly into the chamber to bring the fused portion of the metal into contact with said die.

9. In an apparatus of the character described, a casing providing a work chamber, a holder for supporting a metallic rod forming a work piece from which a casting is to be produced, a holder mounting said rod for downward travel within said chamber, a slideable electrode mounted in a wall of said chamber, a source of current supply connected to said rod and electrode for establishing an electric arc to effect a fusing of a portion of the rod, a detent detachably locking said holder against downward movement, a die movable into and out of alignment with the path of downward travel of said rod, and means for reciprocating said electrode toward and from the rod, locking the holder and rod against downward movement and releasing the same for downward movement and moving said die into and out of the path of downward travel of the rod.

JOSEPH E. JOHNSON
